WILLIAM H. MINER, OF CHICAGO, ILLINOIS.

DRAW-BAR YOKE AND DRAW-BAR-YOKE CONNECTION FOR DRAFT-RIGGING.

1,086,073.

Specification of Letters Patent.

Patented Feb. 3, 1914.

Application filed February 10, 1908. Serial No. 415,019.

To all whom it may concern:

Be it known that I, CHARLES J. NASH, a citizen of the United States, residing in Chicago, in the county of Cook and State of Illinois, have invented a new and useful Improvement in Draw-Bar Yokes and Draw-Bar-Yoke Connections for Draft-Rigging, of which the following is a specification.

My invention relates to improvements in draft rigging for railway cars, and more particularly to improvements in the construction of the draw-bar and draw-bar yoke and draw-bar yoke connection. Its object is to provide an improved construction of draw-bar yoke and means for connecting the same to the draw-bar, and which, at the same time will enable the new construction of draw-bar yoke to be replaced by the old or ordinary construction of draw-bar yoke when necessary for repairs.

The invention consists in a draw-bar furnished on its upper and lower faces with recesses having curved or concave wedging or hook-shaped gibs or shoulders at their rear ends adapted to receive correspondingly shaped circular bosses on the inner side of the upper and lower members of the yoke, thus giving the yoke a limited flexibility in respect to the draw bar, while at the same time affording a very secure and strong attachment of the yoke to the draw bar against pulling strains, combined with upper and lower front abutment or filler blocks fitting in the recesses on the upper and lower sides of the draw bar and overlapping the flanges of the circular bosses on the upper and lower members of the draw bar yoke, and thus affording a very strong and secure attachment of the yoke to the draw bar against buffing strains. The inclined or wedging form of the underface of the curved gib or shoulder on the draw bar at the rear end of the recess therein, in connection with the correspondingly shaped flange of the circular boss on the inner sides of the upper and lower members of the yoke, causes the yoke members to hug or clamp the draw bar and thus to increase the strength and security of the attachment of the yoke to the draw bar. The yoke is preferably made of malleable iron and provided with integral transverse webs at its middle portion for engagement with the middle followers; these transverse webs also serving to strengthen the yoke and to prevent its upper and lower

members from buckling under heavy blows or strains.

In the accompanying drawing, forming a part of this specification, Figure 1 is a side elevation of a draft rigging draw-bar and yoke embodying my invention; Fig. 2 is a plan view; and Fig. 3 is a detail perspective view showing one of the front abutment or filler blocks employed with the new or improved construction of yokes.

In the drawing A represents a draw-bar, B the improved yoke, and D, D the front abutment or filler blocks employed with the improved yoke.

The draw bar A is provided at its rear end on its upper and lower sides with recesses A¹ to receive the filler blocks D, D. These recesses A¹ have, preferably, straight square shoulders a at their front ends and circularly curved undercut or hook-shaped gibs or shoulders a² at their rear ends, the under faces a² of which are preferably inclined or wedging.

The draw bar yoke B is preferably cast and of malleable iron and has its upper and lower members b and b¹ furnished on their inner sides at the front ends thereof with integral circular bosses b², having curved flanges b³ adapted to fit the curved and undercut gibs or shoulders a² of the draw bar A and snugly engage the same. The draw bar yoke B is also preferably furnished with integral transverse webs b⁴ at its middle portion for engagement with the two middle followers of the tandem spring draft rigging.

The front abutment or filler blocks D which may be removed or replaced fit in the recesses A¹ of the draw bar between the front shoulders a thereof and the circular curved front face of the yoke bosses b², and each has a square shoulder d at the front end thereof to abut against the front shoulder a of the draw bar recess A¹, and a circularly curved concave rear shoulder d¹ to fit against the corresponding convex yoke boss b². The concave shoulder d¹ has a concave undercut or shoulder d² with an inclined face d³ to overlap the flange b³ of the circular boss b² of the yoke. The front abutment or filler blocks D in connection with the shoulder a of the draw bar and the curved bosses b² of the yoke, thus afford a strong, safe and secure connection between the draw bar and yoke in resisting buffing.

strains or blows, while the circularly curved and hook-shaped gibbs or shoulders a^1 of the draw bar, in connection with the flanged bosses b^2 of the yoke, afford a strong and 5 secure connection between the draw bar and yoke against pulling strains. This connecting means between the draw bar and yoke also permits flexibility between the draw bar and yoke and thus enables the draw bar to 10 swing laterally as required in passing around curves.

A rivet or bolt E passing through the connecting blocks D D and draw bar secures the connecting blocks D in place. The rivet 15 G may be preferably also inserted centrally through the yoke bosses b^2 and the draw bar, the draw bar having suitable holes a^3 a^4 to receive said rivets or bolts. The draw bar is also preferably provided with a further 20 rivet hole a^5 for use when the ordinary construction of yoke is employed, as occasion may require for repairs or other purposes.

I claim:

In combination: a draw bar provided with 25 recesses on its upper and lower sides having concavely curved, rear shoulders, each shoul-

der being provided with a beveled undercut portion; a yoke having inwardly projecting circular bosses at the front ends of the upper and lower members, snugly fitting said 30 concavely curved shoulders, each of the bosses being provided with a circular flange beveled to coöperate with the beveled undercut portions of the draw bar shoulders; and removable upper and lower front filler blocks 35 having concavely curved, rear shoulders snugly fitting the curved end bosses of the yoke, each of the filler block shoulders being provided with beveled, undercut portions corresponding to the beveled flanges of the 40 bosses, the beveled, undercut portions of the draw bar shoulders, and the filler block shoulders, and the beveled boss flanges, co-operating under buffing and pulling strains to draw the ends of the upper and lower 45 yoke members inwardly, substantially as specified.

CHARLES J. NASH.
